UNITED STATES PATENT OFFICE

152,892

DESIGN FOR A COMBINATION TIE RACK AND MIRROR

Walter W. Lindsey, Sunland, Calif.

Application June 17, 1947, Serial No. 139,739

Term of patent 14 years

(Cl. D33—8)

To all whom it may concern:

Be it known that I Walter W. Lindsey, a citizen of the United States and residing at Sunland, in the county of Los Angeles and State of California, have invented a new, original, and ornamental Design for a Combination Tie Rack and Mirror, of which the following is a specification, reference being had to the accompanying drawing, forming a part thereof.

Figure 1 is a front elevational view of a combination tie rack and mirror showing my new design.

Fig. 2 is a side elevational view thereof with the lower portion thereof shown in section as taken on line 2—2, Fig. 1.

Fig. 3 is a top plan view of my new design as viewed from the top of Fig. 1.

I claim:

The ornamental design for a combination tie rack and mirror, as shown.

WALTER W. LINDSEY.
